ADJUSTABLE SHORE

Filed March 11, 1927

UNITED STATES PATENT OFFICE

CHARLES M. MARKHAM, OF INDIANAPOLIS, INDIANA

ADJUSTABLE SHORE

Application filed March 11, 1927. Serial No. 174,657.

It is the object of my invention to produce an adjustable shore which may be economically manufactured and which will be positive and safe in operation.

5 I accomplish the above object by forming my shore of two parts one of which serves as a base; and in this base I support a dog which may be moved into and out of locking engagement with the other shore-part by a wedge or 10 other suitable means which operates normally to hold the dog in locking position.

The accompanying drawings illustrate my invention: Fig. 1 is a perspective view of my shore; Fig. 2 is a section on the line 2—2 of 15 Fig. 3 illustrating the construction of the locking dog and the wedge which operates it; Fig. 3 is a vertical section on the line 3—3 of Fig. 2; and Fig. 4 is a fragmental elevation showing a raising lever applied to my 20 shore.

As stated above, my shore includes a base conveniently formed of a base plate 10 and two upright opposed channels 11 at the upper ends of which is located a head 12. If desired, suitable cross pieces 13 may be provided 25 between the base plate 10 and the head 12. The other part of the shore is in the form of a rectangular member conveniently a square timber 15 which is received within the 30 channels 11 and is vertically slidable therein.

At one side of the head 12, it is provided with a hollow extension 17 having a bottom wall 18 and a top wall 19 which are both provided with slots for the reception of a movable wedge or key 20. Desirably, the sides of the key 20 are grooved so as to make the key of I-shaped cross section. Desirably, also, the bottom and top walls 18 and 19 of the head-extension 17 are provided with ears 22 which enter the grooves in the opposite faces of the key 20, such grooves originally extending to one end of the key and being closed after the key is inserted in the head extension 17 by means of ribs 23 which may be formed by welding and which extend between the flanges 24 of the key to prevent removal of the key after it is once in place.

Within the hollow head-extension 17 is located a dog 26. This dog fits loosely within the head extension 17 in order that it may be

free to move in and out or up and down. Passing horizontally through this dog parallel to the adjacent face of the member 15 is a rotatable pin 27 provided with a transverse T-shaped groove for the reception of the inner key-flange 24, the outer face of the dog 26 being notched to permit passage of the key. 55

The inner face of the dog 26, or that face which engages the member 15, is roughened and is convexly curved eccentric to the axis 60 of the pin 27 so that it will always engage the member 15 at a point above the axis of the pin. This is clear from Fig. 3.

The wedge 20 is preferably arranged so that its wider end is uppermost in order that the 65 force of gravity acting on it will tend to draw it downward, thus forcing the dog 26 inward against the face of the member 15. The locking action thus obtained is sufficient to hold the member 15 in any position against the 70 force of gravity.

To raise the member 15 to its desired location, I may employ the raising mechanism illustrated in Fig. 4 which consists of an operating lever 30 connected by a link 31 to a 75 yoke 32 which straddles the timber 15 above the head 12. The inner end of the lever 30 rests on a lip 33 provided on the side of the head 12 to act as a fulcrum for the lever. The yoke 32 is somewhat wider than the member 80 15 in order that it will grip such member only when tilted relatively thereto. With this construction, alternate raising and lowering of the outer end of the lever 30 will produce a 85 step-by-step upward movement of the member 15, the dog 26 operating to hold the member against downward movement when the yoke 32 is being lowered thereon.

When the member 15 has been raised into contact with the part against which it is to 90 act, the wedge 20 is driven downward in the head-extension 17. This downward movement of the wedge tends to move the dog 26 inwardly into firm engagement with the member 15. At the same time, since the force exerted on the dog by the wedge is applied below the point of engagement of the dog 26 and member 15, downward movement of the wedge also tends to tilt the dog to raise its inner end thus raising the member 15. By 95 100

this action the dog 26 and member 15 move from the full line position illustrated in Fig. 3, which position they occupy at initial locking of the dog, to the dotted line position illustrated in Fig. 3. In addition to the upward movement of the member 15 produced by tilting of the dog 26, a further tendency to upward movement is produced by inclining the bottom wall 18 of the head extension 10 so that it will act as a guide to cause the dog 26 to be raised when moved inward thereon. To make the head of the wedge more accessible when it is being driven into locking position, the wedge is preferably curved outward as is clear from Fig. 3.

In this application, my shore is described as if it occupied a vertical position, for this is the position in which the shore is most frequently used. The shore can, however, be used in any position where an adjustable compression brace may be desired.

I claim as my invention:

1. A shore comprising a first member provided with a loop as an element of a telescopic joint, a second member shiftable out of said loop in telescopic joint assembly with the first member, a gripping element mounted in the loop for movement relatively to the members, a wedge actuator for the gripping element, and intermediate transmission means between the wedge and element, shifting the element into gripping position with the second member and thereby outward from the loop.

2. A telescopic connection embodying a pair of members, a fitting engaging one member, a grip element in the fitting engaging the other member, a directing mounting in the fitting determining an axis for rocking of the element, and thrust means for shifting the element and mounting toward the direction of extent of one of the members from the fitting.

3. A telescopic load receiving connection embodying a pair of members, a fitting engaging one member, a gripping element co-acting to connect the fitting to the other member, there being a directing mounting determining an axis for rocking the element as to the fitting, and thrust means for shifting the element and mounting longitudinally of the connection and against the load receiving direction of the connection.

4. A telescopic load receiving connection embodying a lower first member, an upper second member, a fitting therebetween, a gripping element assembled with the members by the fitting, there being a directing mounting determining an axis for rocking of the element as to the fitting, and thrust means for shifting the element and mounting for moving the element relatively to the first member and along the second member against the direction of load for thrusting of the second member longitudinally out of the first member.

5. A shore comprising a first member embodying a loop for a telescopic joint, a second member movable longitudinally out of said loop of the first member for shore extension, a shiftable element and directing means at the loop, determining the path of shifting of the element relative to the first member, said element in its shifting having a component along the second member away from the first member and out of said loop, and an actuator for said shifting of the element mounted by one of the members and movable relatively to the members and element.

6. A telescopic connection embodying a pair of members, a fitting engaging one member providing a pocket, a member engaging element in the pocket shiftable relatively to the fitting and into engagement with one member and relatively to the other member, a rocker in the fitting engaging the element, and an actuator providing a bearing for engaging and shifting the rocker.

7. A telescopic connection embodying a pair of members, a fitting engaging a member providing a pocket, a member engaging grip element in the pocket, and thrusting control means for shifting the element relatively to the fitting away from the direction of a member extent from the fitting comprising a working member rockably seated in the element, and a wedge for operating the working member.

In witness whereof, I have hereunto set my hand at Indianapolis, Indiana, this 4th day of March, A. D. one thousand nine hundred and twenty seven.

CHARLES M. MARKHAM.
